CLAIM

What is claimed the ornamental design for a lighting module LED light board, as shown and described.

DESCRIPTION

FIG. 1 is a top, perspective view of a lighting module LED light board showing my new design;

FIG. 2 is a front view of the lighting module LED light board of FIG. 1, shown increased in scale for clarity;

FIG. 3 is a rear view of the lighting module LED light board of FIG. 1, shown increased in scale for clarity;

FIG. 4 is a left, side view of the lighting module LED light board of FIG. 1;

FIG. 5 is a right, side view of the lighting module LED light board of FIG. 1;

FIG. 6 is a top view of the lighting module LED light board of FIG. 1;

FIG. 7 is a bottom view of the lighting module LED light board of FIG. 1; and,

FIG. 8 is a perspective view, with parts separated, of a lighting assembly including the lighting module LED light board of FIG. 1, with components of the lighting assembly shown in broken lines for illustrating environment of the lighting module LED light board of FIG. 1;

The broken lines provided in the drawings form no part of the claimed design.

Applicant reserves the right to amend the claimed invention by showing in solid lines any and all features or portions thereof originally shown in broken lines and/or by showing in broken lines any and all features or portions thereof originally shown in solid lines.

1 Claim, 4 Drawing Sheets
